UNITED STATES PATENT OFFICE.

SAMUEL T. WELLMAN AND HORACE W. LASH, OF CLEVELAND, OHIO, ASSIGNEES TO THE LIQUID FORGED STEEL COMPANY, OF CLEVELAND, OHIO, A CORPORATION OF OHIO.

APPARATUS FOR HANDLING INGOT-MOLDS.

1,073,196.

Specification of Letters Patent. Patented Sept. 16, 1913.

Application filed December 19, 1912. Serial No. 737,593.

To all whom it may concern:

Be it known that we, SAMUEL T. WELLMAN and HORACE W. LASH, citizens of the United States, and residents of Cleveland, 5 in the county of Cuyahoga and State of Ohio, have invented a certain new and useful Improvement in Apparatus for Handling Ingot-Molds, of which the following is a full, clear, and exact description.

10 The object of this invention is to facilitate the practice, on a commercial scale, of that method of casting ingots which involves the use, in connection with each ingot mold, of a jarring machine on which the 15 mold is supported while the molten metal therein is solidifying.

The invention includes a suitable number 20 of jarring machines arranged in a row, an adjacent parallel track for guidance of a train of cars or buggies on which the empty molds may be brought to and the filled molds carried from the jarring machines, a second adjacent parallel track, and a mold handling machine which runs on the latter track, 25 and is provided with means wherewith to transfer molds from the jarring machines to the cars, and vice versa.

The invention is shown in the accompanying drawing and hereinafter fully described 30 and definitely pointed out in the appended claims.

In the drawing, Figure 1 is an end elevation of an apparatus embodying the invention. Fig. 2 is a plan which shows a plurality of jarring machines, an adjacent track and a train of mold-carrying cars thereon and a second track and the mold handling machine thereon. In both of these views the mold handling machine is shown more 35 or less diagrammatically. That is to say, without any attempt to show the construction. Fig. 3 is a plan view of a suitable mold handling machine and a mold carrying car and several adjacent jarring machines. Fig. 4 is a side elevation of the 40 same parts. Fig. 5 is a sectional end view of the mold handling machine in the plane indicated by line 5—5 on Fig. 4; and Fig. 6 is a sectional end view in the plane indicated 45 by line 6—6 on Fig. 4.

Referring to the parts by letters, A¹, A², A³, A⁴, A⁵, A⁶, A⁷, A⁸, A⁹, and A¹⁰ represent jarring machines which are arranged in a row. Since these jarring machines may 50 vary widely in construction; provided they

are capable of supporting an ingot mold and of applying thereto a succession of vertical vibrations while the metal is solidifying, it has not been thought necessary to show their construction in detail. Adjacent 60 to and parallel with this row of jarring machines is a track B for the guidance of a train of cars C. Adjacent to and parallel with the car track mentioned are the rails F, F, which constitute a track for the mold 65 handling machine D. This machine is shown rather diagrammatically in Figs. 1 and 2, but is shown with the necessary detail in Figs. 3 and 6, inclusive. The particular construction of this machine is not 70 material to this invention, except to this extent, to wit, the machine must be capable of movement along its track, and must be provided with means by which the ingot molds M may be lifted and transferred from the 75 several jarring machines to the cars, and vice versa. There is also a traveling crane K, or its equivalent, which is movable in a path which is parallel with the tracks B and F. This crane is provided for the purpose 80 of carrying the ladle L into positions such that it may pour molten metal into any mold on any of the jarring machines. This crane carries a pouring platform P upon which the operator may stand in order to manipulate 85 the valve of the ladle.

As stated, the purpose of this apparatus is to economically practise a process of producing ingots which does not permit the common practice of filling the molds 90 while they are on cars. The process for which this apparatus is adapted is one which requires that, when the metal is solidifying in the molds, such molds must be supported on jarring machines. These jarring machines are rather expensive; and economical practice requires that each shall be in use as constantly as possible. Let us assume, therefore, that on each jarring machine A¹ to A¹⁰, inclusive, is a filled mold, 100 and that the metal in said mold has become solid. That is to say, the mold is ready for removal. The problem of how to remove these filled molds and substitute for them empty molds, in the shortest time, 105 and with the expenditure of the least energy; is that which this invention solves by operating in the following manner. Under the stated conditions, a train of cars C is run in on the track B. On these cars are at 110

least as many empty ingot molds M as there are filled molds on the jarring machines to be removed. Additionally there must be on this train of cars and preferably at one 5 end thereof, say, for example, the left end, as shown in Fig. 2, an empty space capable of receiving a mold. This train of cars is stopped with this empty space adjacent to the right hand jarring machine A¹ as 10 shown in Fig. 2. The mold handling machine is then moved to a position such that its mold handling arm is adjacent to this vacant space on the car. The mold handling arm is then moved over the car until 15 the jaws carried by said arm embrace the filled mold on the jarring machine A¹. This mold is lifted and moved over and deposited on the car in the vacant space referred to. Then and before the jaws have 20 let go their hold upon this filled mold, the mold handling machine D will be moved to the left, as shown in Fig. 1, thereby moving the train of cars along until the first or left empty mold thereon is adjacent to the 25 now empty jarring machine A¹. Then the mold handling arm is operated in such wise that it takes this empty mold from the car and deposits it upon the jarring machine A¹, thereby leaving an empty space on the car. 30 Then the mold handling arm is drawn back so that it may contact with the filled mold which has been deposited on the car, and then the mold handling machine is moved to the left, thereby moving the train of cars 35 until the empty space created by moving a mold from the car to the jarring machine A¹ comes opposite jarring machine A². Then the mold handling arm is operated, as before described, to lift the filled mold 40 from jarring machine A² and deposit it in the vacated space on the car. These operations are repeated until the filled molds have been taken from all of the jarring machines and put onto the cars and empty 45 molds have been taken from the cars and put onto all of the jarring machines. As shown in Fig. 2 five filled molds have been removed from the jarring machines and deposited on the cars. 50 As molds are put onto the jarring machines the crane K may be moved along so that the molds on the jarring machines may be filled with molten metal from the ladle L. When all of the filled molds have 55 been transferred to the train of cars, this train may be run out to a suitable place, where the ingots may be withdrawn from said molds. While this is being done, the jarring machines are in operation agitating 60 and jarring the molten metal which has been put into the molds from the traveling ladle. This method of handling molds is such as to involve a minimum expenditure of energy in transferring the molds from 65 the cars to the jarring machines, and vice

versa, and to involve a minimum of delay in the operation of the jarring machines.

The mold handling machine as shown includes a built up truck or body comprising two side members, two transverse beams 2, and wheels 3 adapted to run on track rails F. A transversely movable carriage 4 is movably supported on this truck. On this carriage are two shafts 6 and 7, one located above and one below the beams 2. Wheels 8 fixed to shaft 6 run on top of the beams 2 and other wheels 9 fixed to shaft 7 lie beneath and may engage the lower edges of the beams 2. On this carriage an electric motor 10 is mounted, and this is connected by a suitable train of gearing with the two shafts 6 and 7, whereby these shafts and the wheels thereon may be turned in either direction to cause this carriage to move along the beams 2,—that is to say, transversely of the truck. A built up jaw carrying arm 12 is rigidly fixed to and forms a part of this carriage. This beam rests upon and is supported by two rollers 14, each of which is mounted in the outer end of a horizontal arm 15, which is secured to a rock shaft 16. Two vertically extended arms 17 are likewise fixed to this rock shaft. The upper ends of these arms are connected by links 18 with a cross head 19, which cross head is connected by links 19^a with the cross head 20 of a pressure fluid motor 20^a which is carried by the truck frame. By the operation of this motor the cross head is moved to the right or left, thereby causing the 100 rocking of shaft 16 and the consequent raising or lowering of the free end of the arm 12. Pivoted to this arm 12 and extending to the left beyond the end of said arm are two jaws 22. The front ends of these jaws 105 are shaped so that they may take hold of the ingot molds. Their rear ends are inclined away from each other, as shown. A reciprocating cross head 23 is movably mounted in the arm 12, and it is connected with the piston rod 24 of a fluid pressure motor 25 which is fixed to the rear end of the arm 12. The cross head 23 carries four vertical studs 26, 28, whereon are friction rollers 27 which engage with the outwardly inclined rear ends of the jaws 22. By moving this cross head outward the studs 26 by engaging the inclined inner faces of the rear ends of the jaws will be caused to close in upon a mold. In moving the cross head 110 in a reverse direction the studs 28 will engage the outer inclined surfaces at the rear end of the jaws, and the jaws will be caused to open. The shaft 30 is mounted on one end of the truck and extends from one side to the other thereof. Two drums 31 are fixed to this shaft, and an electric motor 32 is provided for turning the shaft in one direction or the other. Cables 33 are wound upon these drums and extend therefrom in 115 120 125 130

both directions, and the ends of these cables are dead ended, that is to say, secured to fixed supports. By turning these drums, the cables will be taken in from one direction and paid out in the other direction, and thus the mold handling machine will be caused to traverse the tracks.

Having described our invention, we claim:

- 10 1. In an apparatus for handling ingot molds, the combination of a row of jarring machines adapted for the support of ingot molds, a track alongside of and parallel with said molds, cars on said track adapted to support ingot molds, another adjacent parallel track, a mold handling machine running on the latter track, and mechanism carried by said machine adapted to move molds from the jarring machines to the 20 cars and from the cars to the jarring machines.
- 25 2. In an apparatus for handling ingot molds, the combination of a row of jarring machines adapted for the support of ingot molds, a track alongside of and parallel with said molds, cars on said track adapted to support ingot molds, another adjacent parallel track, a mold handling machine running on the latter track, mechanism

carried by said machine adapted to move 30 molds from the jarring machines to the cars and from the cars to the jarring machines, and another parallel guideway, a support movable thereon, and a metal ladle carried by said support.

3. In an apparatus for handling ingot molds, the combination of a row of jarring machines adapted for the support of ingot molds, a track alongside of and parallel with said molds, cars on said track adapted to support ingot molds, another adjacent parallel track, a mold handling machine running on the latter track, mechanism carried by said machine adapted to move 40 molds from the jarring machines to the cars and from the cars to the jarring machines, another parallel guideway, a support movable thereon, a metal ladle carried by said support, and a pouring platform suspended from said movable support.

In testimony whereof, we hereunto affix our signatures in the presence of two witnesses.

SAMUEL T. WELLMAN.
HORACE W. LASH.
